PARTS CLEANSING MACHINES

Lester J. N. Keliher and Leonard L. Northrup, Jr.,
Dallas, Tex.

Application October 4, 1951, Serial No. 249,652

19 Claims. (Cl. 134—105)

This invention relates to cleansing machines and more particularly to a cleansing machine having a rotatable impeller for circulating cleansing liquid in a tank.

It is desirable during repair or maintenance operation to cleanse the parts of internal combustion motors, and the like. Since these parts are usually covered with grease or oil impregnated dirt which adheres strongly to the parts, the cleansing machine employed to free the parts of this dirt, oil and grease must heat the cleansing liquid in which the parts are immersed in order to expedite the action of such liquid and must circulate the cleansing liquid violently about the parts in order to mechanically remove the adhering dirt from the parts. The tank of the cleansing machine should preferably be provided with a settling basin to prevent recirculation of dirt which has been removed from the parts; and the rotatable impeller mounted in the tank for circulating the cleansing liquid should be so disposed relative to the settling basin that rotation of the impeller will not stir up the dirt settled in the settling basin. Moreover, the tank should be of such conformation that the tendency of the impeller to displace the body of cleansing liquid from the center toward the circumference of the tank in a vortex and leave the central portion of the tank free of liquid is overcome, and the liquid is forced to circulate throughout all portions of the interior of the tank to bring the cleansing liquid into intimate violent contact with all surfaces of parts placed in the tank for cleansing. In addition, the shaft of the impeller, which usually extends downwardly through the bottom of the tank, should be provided with a seal which prevents leakage of cleansing liquid from the tank past the bearings of the shaft.

Accordingly, it is an object of the invention to provide a new and improved cleansing machine.

It is another object of the invention to provide a new and improved cleansing machine having an improved rotatable impeller for circulating cleansing liquid in a tank.

Still another object of the invention is to provide a new and improved cleansing machine having means mounted in a tank for heating a cleansing liquid circulated through the tank by an impeller, and so disposed that the liquid is constantly directed into contact with the heating means.

A further object of the invention is to provide a new and improved cleansing machine having a tank provided with a settling basin and an impeller rotatably mounted in the tank to circulate cleansing liquid throughout the tank without materially reagitating or stirring up dirt settled in the basin.

It is still further object of the invention to provide a new and improved cleansing machine having a tank of such conformation as to overcome the tendency of an impeller mounted in the tank to displace the body of cleansing fluid in a vortex from the center toward the circumference of the tank.

It is another object of the invention to provide a new and improved cleansing machine having an impeller whose

2

shaft is provided with a seal maintained in an air pocket while the impeller is rotated.

Still another object of the invention is to provide a rotatable shaft with a seal and with means for forming and maintaining an air pocket about the seal.

Briefly stated, the new and improved cleansing machine includes a tank having a heater disposed adjacent but spaced from the bottom of the tank and supported on radially extending vanes. An impeller mounted in said tank for rotation about a vertical axis agitates and propels cleansing liquid upwardly past the heater. The tank is provided with an outwardly extending bay or interrupter chamber which, in conjunction with the supporting vanes, overcomes the tendency of the impeller to displace the cleansing liquid in a vortex outwardly from the center toward the circumference of the tank. The impeller is provided with vertical fins extending upwardly from a substantially horizontal circular base which overlies a settling basin and prevents undue disturbance of the dirt which may have settled in the base. The impeller is also provided with a dependent hood or skirt which telescopes over a vertical bearing sleeve. The bearing sleeve is provided with an air passage communicating with the vertical annular space between the skirt and bearing sleeve, and air may pass through this passage to displace liquid from between the upper portion of the skirt and sleeve and form and maintain an air pocket therebetween. A grease seal is disposed in said bearing sleeve to seal between the bearing sleeve and the impeller shaft which extends therethrough. In another embodiment of the invention, the skirt may be provided with transverse apertures through which liquid is expelled from between the sleeve and the skirt as the skirt is rotated. A further embodiment employs a skirt provided with a helical screw which also expels liquid from between the sleeve and the skirt as the skirt is rotated.

Additional objects and advantages of the invention will readily be apparent from the reading of the following description of a device constructed in accordance with the invention, and reference to the accompanying drawings thereof, wherein:

Figure 1 is a perspective view of the cleansing machine, some portions being broken away to reveal the interior of the tank and the components disposed therein;

Figure 2 is an enlarged fragmentary elevation, some parts being broken away to show certain details of construction, showing the heater controls;

Figure 3 is an enlarged vertical sectional view showing the impeller and bearing sleeve structure;

Figure 4 is a view similar to Figure 3 showing a modified form of the impeller skirt provided with apertures to pump liquid from between the impeller skirt and the bearing sleeve;

Figure 5 is a similar view of another modified form of the impeller skirt provided with a helical screw to expel liquid from between the impeller skirt and the bearing sleeve;

Figure 6 is a sectional view taken on the line 6—6 of Figure 5; and

Figure 7 is a side view of a modified form of the cleansing machine, some portions being broken away to reveal the interior of the tank and the components disposed therein.

In the drawings, the numeral 10 designates a cleansing machine which includes a tank 11 mounted on a plurality of vertical legs 12. A shield 13 formed by a pair of rings 14 and 15 and a wire grill 16 extending therebetween is disposed beneath the tank and around the supporting legs. The tank has a bay or interrupter chamber 17 extending outwardly from one side thereof for a purpose to be set forth below. The open upper end of the

tank is closed by a cover 18 pivotally secured to the vertical walls of the tank by a pair of brackets 19 and 20 secured to the cover and a pair of brackets 21 and 22 secured to the wall of the tank, and a rod 23 extends through registering apertures in the brackets, the brackets being rotatable thereon. The brackets 21 and 22 may be welded to the tank while the brackets 19 and 20 may be welded to reinforcing straps 24 and 25, respectively, secured to the cover 18 by screws 26. A handle 27 is mounted on the reinforcing straps and the cover by the pair of screws 28. While particular methods of securing the brackets, the reinforcing straps, and handle to their associated elements have been particularly described, it will be apparent that other conventional methods of securing these elements to the tank and cover may be employed.

The tank 11 has a convex bottom 29 provided with central circular aperture 30. A settling basin 31 having a vertical annular wall 32 is secured to the bottom of the tank by welding or in any other suitable conventional manner. The bottom 33 of the settling basin inclines downwardly toward an outlet 34, and is provided with a central aperture 35 which is preferably concentric with respect to the central aperture 30 of the tank bottom 29.

A bearing sleeve 36 extends upwardly into the interior of the tank 11 through the central apertures of the bottom of the settling basin and the tank, and is rigidly secured to the settling basin by a number of threaded studs 37 extending through suitable apertures in a circular inclined flange 38 integral with the bearing sleeve into threaded bores in the bottom 33 of the settling basin. A lock washer 39 and a nut 40 threaded on each stud hold the inclined flange and bearing sleeve in place on the settling basin, and a gasket 42 clamped between the flange and the bottom of the settling basin seals against fluid leakage therebetween. Since the flange 38 is inclined complementary to the bottom of the settling basin, and the bearing sleeve is disposed axially of the settling basin, a semi-annular vertical wall 43 is formed partially surrounding the bearing sleeve but spaced therefrom. The purpose of the space between the bearing sleeve and the semi-annular wall will be hereinafter explained.

The shaft 44 of the impeller 45 extends axially through the bearing sleeve and is rotatably supported therein by a pair of spaced ball bearing assemblies 46 and 47 and a pair of retaining rings 48 and 49. The upper bearing assembly includes an outer race 50 resting on an annular ledge 51 provided by an enlargement of the central bore of the bearing sleeve, a plurality of balls 52, and an inner race 53 disposed about the impeller shaft. The upper retainer ring 48 is disposed in an annular recess in the impeller shaft and extends outwardly over and about the inner race 53 to limit the downward movement of the impeller shaft relative to the bearing sleeve. The lower retaining ring 49 is disposed in an annular recess in the impeller shaft spaced below the bearing and serves to limit the upward movement of the impeller shaft by abutting the inner race of the upper bearing, and to permit removal of said upper bearing in disassembly. The lower ball bearing assembly 47 similarly includes an outer race 56 disposed in an enlargement 57 of the lower end of the central bore of the bearing sleeve, a plurality of balls 58, and an inner race 59 disposed about the impeller shaft.

The upper reduced end or hub 60 of the impeller shaft extends through a central bore 61 in the upper boss 62 of the impeller 45, a lock screw 63 threaded in a bore formed partly in the impeller shaft and partly in the boss 62 locks the impeller against rotation on the shaft. A bolt 64 threaded in a central bore in the upper end of the shaft bears against a washer 65 and compresses a gasket 66 interposed between the washer and the upper end of the shaft. The bolt 64 and washer 65 prevent axial movement of the impeller on the impeller shaft, since the impeller is held thereby against an annular

ledge 67 formed by the reduction of the upper end of the impeller shaft.

The bore of the boss 62 of the impeller is also provided with an annular recess 68, in which is disposed a seal ring 69 for sealing between the impeller shaft and the impeller. The gasket 66 and the seal ring 69 prevent leakage of air or liquid between the upper reduced portion of the impeller shaft and the impeller.

A seal assembly 70 is provided between the impeller shaft and the bearing sleeve 36, and includes an upper seal assembly 71 and a lower seal assembly 72. The upper seal assembly comprises a resilient annular sealing member 73 held in an annular metallic retainer member 74 (see Fig. 5). The resilient annular sealing member 72 has a flexible lip or flange 75 formed in its inner portion turned upwardly and inwardly toward a seating sleeve 76 which is rigidly secured on the impeller shaft 44 below the hub 60 thereof. The flange 75 of the resilient annular sealing member may be forced outwardly into sealing engagement with the seating sleeve of the shaft by fluid pressure.

The lower seal assembly 72 rests on an annular ledge 78 in the bearing sleeve 36 and seals between the bearing sleeve and the impeller shaft. The annular space between the upper and lower seal assemblies, and between the shaft seating surface 76 and the bearing sleeve 36 is preferably packed with grease.

In order to insure that no liquid will pass between the bearing sleeve 36 and the impeller shaft 44 even if the seal assembly 70 should fail for any reason to make a perfect seal, air is directed to the cylindrical space 79 between the bearing sleeve and the dependent tubular skirt 80 of the impeller 45 through a passage 81 provided in the bearing sleeve. The passage is preferably formed in a vertical ridge or enlargement 82 (Fig. 6) integral with the bearing sleeve, and is enlarged and threaded at its outer end 83 to receive the threaded fitting 84 on the end of a conduit 85 whose upper end is higher than the uppermost level to which the tank is filled with liquid.

It will be apparent now that air trapped in the cylindrical space 79 will prevent liquid from reaching the upper end of the bearing sleeve. Should this trapped air leak out past the seal assembly 70, the liquid will tend to rise and completely fill the space between the skirt and the bearing sleeve. While the impeller is stationary, the seal assembly will, even if not in proper condition, prevent leakage of liquid. When the impeller is rotated, however, the outward movement of the liquid caused by rotation of the impeller will create a pressure differential between the settling basin and the interior of the tank which will tend to draw the liquid from the cylindrical space 79. Air will then be drawn through the conduit 85 into the cylindrical space again to form an air pocket at the upper end thereof. It is preferable that the conduit 85 be connected to a supply of compressed air so that air under pressure may be continually supplied to the cylindrical space, thus insuring that the air pocket will always be present.

In the modified form of the impeller skirt illustrated in Figure 4, a plurality of circumferentially spaced apertures 86 are provided in the skirt 80a adjacent its lower end and below the upper end or outlet of the passage 81. The apertures are slightly inclined from the true radial alignment, so that as the skirt is rotated liquid will be forced or pumped out from the cylindrical space through said apertures, thus insuring the maintenance of an air pocket in the upper portion of the bore of the impeller skirt.

Still another modified form of the skirt 80 is illustrated in Figure 5. In this form the skirt 80b is provided with an internal spiral groove in which is disposed a helical vane or screw 87 which extends into the cylindrical space 79 between the skirt and the bearing sleeve. The turns of the helical groove are so disposed that the turns of the helical vane are inclined upwardly in the direction

of rotation of the impeller skirt. Thus, when the impeller is rotated, the screw 87 will force liquid out of the cylindrical space in the conventional manner.

It will be apparent that compressed air may be supplied to the cylindrical space through the passage 81 in a machine having either of the two modified forms of the skirt, if so desired.

The impeller 45 is rotated by a motor 88 mounted in a motor housing 89 secured to the tank 11 in any suitable conventional manner. A substantially U-shaped grill shield 90 may be mounted below the motor housing. The motor shaft 91 is provided with a drive pulley 92 which is connected to a pulley 93 on the lower end of the impeller shaft 44 by a pair of belts 94.

The tank is provided with a plurality of spaced substantially radially extending supporting vanes 95 which are welded or otherwise suitably secured to the concave bottom 29 of said tank. A substantially U-shaped tubular heater tube 96 is supported on the vanes 95 and has its ends extending outwardly through the wall of the tank. One end 97 of the heater tube may be connected to an exhaust stack, not shown, while the other end 98 of the heater has disposed therein a main burner 99 and a pilot burner 100 which are supplied with fuel from a conduit 101 through a conventional pilotstat 102, a magnetic valve 103 and a shut off valve 104. The pilot burner is provided with fuel by a conduit 105 connected to the pilotstat and is controlled by a thermocouple 106 energized electrically through a conductor or lead 107. The magnetic valve 103 is controlled by a thermostat 108 communicating with the interior of the tank 11 and which electrically actuates the magnetic valve to control the temperature of the liquid within the tank.

The outlet 34 of the setting basin 31 is connected in any suitable conventional manner to a T-shaped two-way valve 109 whose handle may be turned to allow liquid to enter from conduit 111 connected to a source of water, through a shut-off valve 112 and the valve 109 to the settling basin 31 and thence into the tank 11. The settling basin and the tank may be drained into a conduit 113 connected to a sewer line by turning the handle of the valve 109 to another position, thereby allowing the liquid to drain from the settling basin through a shut-off valve 114 into the conduit 113 and thence to the sewer line.

In use, the tank 11 is first filled with water and a detergent, and the burners are lighted to cause the heater tube 96 to heat the water in the tank. The parts to be cleaned are then placed in the tank on a grill 115 supported on the heater. If the parts are long or have projections extending therefrom, end portions of the parts of the projections may be disposed in the bay 17. The cover 18 is then closed and the motor 88 connected across a source of electricity to drive the impeller 45. The liquid in the tank will be driven or swirled upwardly by the impeller vanes 116 about and into intimate contact with all surfaces of the parts, the hot water, aided by the chemical action of the detergent and by the mechanical forces caused by its agitation or swirling, dissolving and removing dirt, grease and oil from the parts. The supporting vanes 95 and the bay 17 prevent the impeller from displacing the water in a vortex from the center toward the circumference of the tank, so that parts placed in the middle of the tank will be fully subjected to the action of the water.

The vanes 116 of the impeller project upwardly from a circular plate 117 which curves upwardly to the central boss 62 of the impeller. The circular plate 117 is of larger diameter than the aperture 30 in the bottom of the tank, and extends toward the concave bottom so that its outer lower peripheral edge lies closely adjacent the bottom. The circular plate of the impeller obviously acts as a baffle and isolates to a considerable degree the liquid in the settling basin from turbulent flow of liquid in the tank, so that dirt and sludge once settled in the basin will not be stirred up and again moved to the tank.

If desired, the conduit 85 may be connected to a source of compressed gas or air to bubble air continually into the cylindrical space 79. The pressure differential between the settling basin and the interior of the tank will, however, serve to maintain an air pocket in the cylindrical space even if air is not forced in through the conduit 85 by external means, the pressure differential created by the action of the impeller causing air to be drawn in.

In the modified forms of the impeller assembly shown in Figures 4 and 5, the liquid in the cylindrical space is expelled either by the pumping action of the apertures 86 in the skirt 80a of Figure 4, or by the pumping action of the helical screw 87 of Figure 5.

In any form, however, an air pocket will be created in the upper portion of the cylindrical space 79 which will prevent the passage of liquid between the impeller shaft 44, the sleeve bearing 36 and the seal assembly 70.

It will be seen that a cleansing machine has been disclosed which includes a tank 11 of irregular conformation which prevents displacement of liquid in the tank from the center to the circumference of the tank in a vortex when the liquid is circulated by a rotary impeller in the tank. Moreover, it will be seen that the tank is provided with a settling basin 31 in which liquid and sludge is isolated from the turbulence of the liquid in the tank by the circular plate 117 of the impeller which extends beyond the sides of the settling basin. Finally, it will be seen that fluid leakage between the impeller shaft 44 and the bearing sleeve 36 in which it is mounted is prevented by a seal assembly 70 and the formation of an air pocket within the bore of the impeller skirt about the upper end of the bearing sleeve and the seal assembly.

In Figure 7 is illustrated a still further modified form of the cleansing machine, in which an elongate tank 118 is provided with two impellers 119 and 120, similar to the impeller 45 of the machine illustrated in Figure 1. The bottom 121 of the tank slopes downwardly from the vertical walls 122 of the tank and from a central raised portion 123 toward two apertures 124 and 125 so that dirt and sludge may settle into the two settling basins 126 and 127, respectively. The outlets 128 and 129 of the two settling basins are connected by conduits 130 and 131, respectively, to a valve 132. The valve 132 controls the passage of fluid into or out of the settling basins, and is connected with a conductor 132a which communicates with supply and exhaust lines in the same manner as the form first described.

The impellers 119 and 120 are mounted for rotary movement in the same manner as the impeller 45 of Figures 1, 3, 4 and 5 and have impeller shafts 133 and 134, respectively, which are driven by a motor (not shown). Conventional pulleys 135 and 136 are rigidly secured to the impeller shaft whereby a belt (not shown) connected to the drive shaft of the motor may simultaneously drive both impellers. The two impellers are preferably driven in opposite directions to decrease the power required to drive them. If both were rotated in the same direction, an undue turbulence or swirling of the liquid would result and a greater force would have to be applied to the impeller shafts to rotate the impeller shafts.

The bottom 121 of the tank is provided with a plurality of vanes 137 disposed substantially radially about each of the impellers and which extend inwardly from the wall 122 of the tank. A heater tube 139, similar to heater tube 96, is supported on the vanes. A grill 140 is supported on the heater tube for supporting parts to be cleansed in the tank.

A bay or interrupter chamber, such as bay 17, is not necessary since the liquid driven by each impeller will be thrown into the path of travel of the liquid driven by the other impeller thereby preventing the displacement of liquid in a vortex from above each impeller toward the circumference of the tank. The vanes 137 will also aid

in preventing such displacement of the liquid. However, a bay (not shown) may be employed, if desired.

The manner of operation of the cleansing machine shown in Figure 6 being similar in all respects to that of the machine shown in Figures 1 to 5, it will not be described in detail.

The foregoing description of the invention is explanatory only, and changes in the details of the construction illustrated may be made by those skilled in the art, within the scope of the appended claims, without departing from the spirit of the invention.

What we claim and desire to secure by Letters Patent is:

1. A cleansing machine including, a tank having a downwardly convergent bottom; a settling basin having an outlet and an inclined bottom sloping toward said outlet, said bottoms having aligned apertures; a bearing sleeve extending upwardly through said apertures; means on said bearing sleeve closing the aperture in the basin bottom; an impeller having an imperforate circular plate having its peripheral edge disposed adjacent and overlying the portion of the bottom of the tank surrounding the aperture therein, whereby said plate provides baffle means substantially separating said tank from said settling basin; a plurality of fins extending upwardly from said plate; a tubular skirt depending from said plate and disposed about said bearing sleeve over substantially the whole length of said bearing sleeve, said skirt being spaced from said bearing sleeve to provide an annular space therebetween; a shaft depending from said impeller and extending downwardly through said bearing sleeve; sealing means between said shaft and said bearing sleeve to prevent leakage of fluid therebetween; and means for expelling liquid from said annular space.

2. A cleansing machine including, a tank having a downwardly and inwardly sloping bottom; a settling basin having an outlet and an inclined bottom sloping toward said outlet, said bottoms having aligned apertures; a bearing sleeve extending upwardly through said apertures; means on said bearing sleeve closing the aperture in the basin bottom; an impeller having an imperforate circular plate having its peripheral edge disposed adjacent and overlying the portion of the bottom of the tank surrounding the aperture therein, whereby said plate provides baffle means substantially separating said tank from said settling basin; a plurality of fins extending upwardly from said plate; a tubular skirt depending from said plate and disposed about said bearing sleeve over substantially the whole length of said bearing sleeve, said skirt being spaced from said bearing sleeve to provide an annular space therebetween; a shaft depending from said impeller and extending downwardly through said bearing sleeve; and sealing means between said shaft and said bearing sleeve to prevent leakage of fluid therebetween, said bearing sleeve being provided with a passage for admitting gas into said annular space above the lower ends of said skirt and sleeve.

3. A cleansing machine including a tank having a bottom; a settling basin having an outlet and an inclined bottom sloping toward said outlet, said bottoms having aligned apertures; said bottom of said tank sloping downwardly and inwardly toward said basin; a bearing sleeve extending upwardly through said apertures; means on said bearing sleeve closing the aperture in the basin bottom; an impeller having an imperforate circular plate having its peripheral edge disposed adjacent and overlying the portion of the bottom of the tank surrounding the aperture therein, whereby said plate provides baffle means substantially separating said tank from said settling basin; a plurality of fins extending upwardly from said plate; a tubular skirt depending from said plate and disposed about said bearing sleeve over substantially the whole length of said bearing sleeve, said skirt being spaced from said bearing sleeve to provide an annular space therebetween; a shaft depending from said impeller and extend-

ing downwardly through said bearing sleeve; and sealing means between said shaft and said bearing sleeve to prevent leakage of fluid therebetween, said bearing sleeve being provided with a passage for admitting a gas into said annular space, said skirt being provided with means for expelling liquid from said annular space when said impeller is rotated.

4. A cleansing machine including a tank having a downwardly and inwardly sloping bottom; a settling basin secured to said tank bottom and having an outlet and an inclined bottom sloping toward said outlet, said bottom having aligned apertures; a bearing sleeve extending upwardly through said apertures; means on said bearing sleeve closing the aperture in the basin bottom; an impeller having an imperforate circular plate having its peripheral edge disposed adjacent and overlying the portion of the bottom of the tank surrounding the aperture therein, whereby said plate provides baffle means substantially separating said tank from said settling basin; a plurality of fins extending upwardly from said plate; a tubular skirt depending from said plate and disposed about said bearing sleeve over substantially the whole length of said bearing sleeve, said skirt being spaced from said bearing sleeve to form a cylindrical space therebetween; a shaft depending from said impeller and extending downwardly through said bearing sleeve; and sealing means between said shaft and said bearing sleeve to prevent leakage of fluid therebetween, said bearing sleeve being provided with a passage for admitting a gas into said cylindrical space, said skirt being provided with a plurality of circumferentially spaced apertures adjacent its lower end whereby liquid is expelled from said cylindrical space when said impeller is rotated.

5. A cleansing machine including, a tank having an inwardly and downwardly sloping bottom; a settling basin secured to said tank bottom and having an outlet and an inclined bottom sloping toward said outlet, said bottom having aligned apertures; a bearing sleeve extending upwardly through said apertures; means on said bearing sleeve closing the aperture in the basin bottom; an impeller having an imperforate circular plate having its peripheral edge disposed adjacent and overlying the portion of the bottom of the tank surrounding the aperture therein, whereby said plate provides baffle means substantially separating said tank from said settling basin; a plurality of fins extending upwardly from said plate; a tubular skirt depending from said plate and disposed about said bearing sleeve over substantially the whole length of said bearing sleeve, said skirt being spaced from said bearing sleeve to form a cylindrical space therebetween; a shaft depending from said impeller and extending downwardly through said bearing sleeve; and sealing means between said shaft and said bearing sleeve to prevent leakage of fluid therebetween, said bearing sleeve being provided with a passage for admitting a gas into said cylindrical space; and a helical screw on said skirt disposed in said cylindrical space for expelling liquid from said cylindrical space when said impeller is rotated.

6. A cleansing machine including, a tank having a downwardly and inwardly sloping bottom, a settling basin having an outlet and an inclined bottom sloping toward said outlet, said bottom having aligned apertures; a bearing sleeve extending upwardly through said apertures; means on said bearing sleeve closing the aperture in the basin bottom; an impeller having an imperforate circular plate, said plate being of greater diameter than the aperture in the frusto-conical bottom and disposed immediately above said tank bottom adjacent the aperture of said tank bottom and providing baffle means whereby liquid in the settling basin is not agitated by rotation of said impeller; a plurality of fins extending upwardly from said plate; a tubular skirt depending from said plate and disposed about said bearing sleeve over substantially the whole length of said bearing sleeve; said skirt being spaced from said bearing sleeve to form a cylindrical

space therebetween; a shaft depending from said impeller and extending downwardly through said bearing sleeve; sealing means between said shaft and said bearing sleeve to prevent leakage of fluid therebetween; and means for expelling liquid from said space.

7. The device of claim 1 characterized in that said tank has a main substantially cylindrical wall extending upwardly from said bottom and a bay extending outwardly from the wall for preventing displacement of liquid in the tank in a vortex from the center to the circumference of the tank.

8. The device of claim 1 characterized in that said tank bottom is provided with a plurality of radially spaced supporting vanes; and a heater disposed on said vanes, said vanes and said heater being disposed in the path of flow of liquid contained in the tank to be engaged by said liquid for preventing displacement of liquid contained in the tank in a vortex from the center to the circumference of the tank.

9. A cleansing machine including, a tank having an inwardly sloping bottom; a settling basin secured to said tank bottom having an outlet and an inclined bottom sloping toward said outlet, said bottoms having aligned apertures; a bearing sleeve extending upwardly through said apertures; means on said bearing sleeve closing the aperture in the basin bottom; an impeller disposed in said tank above said apertures and having a depending tubular skirt disposed about said bearing sleeve over substantially the whole length of said bearing sleeve, said skirt being spaced from said bearing sleeve to form a cylindrical space therebetween; a shaft secured to said impeller and extending downwardly through said bearing sleeve; sealing means between said shaft and said bearing sleeve to prevent leakage of fluid therebetween; and fluid pressure means for expelling liquid from said cylindrical space.

10. A cleansing machine including, a tank having a downwardly and inwardly inclined bottom; a settling basin secured to said tank and having an outlet and an inclined bottom sloping toward said outlet, said bottoms having aligned apertures; a bearing sleeve extending upwardly through said apertures; means on said bearing sleeve closing the aperture in the basin bottom; an impeller disposed in said tank above said apertures and having a dependent tubular skirt disposed about said bearing sleeve over substantially the whole length of said bearing sleeve, said skirt being spaced from said bearing sleeve to provide an annular space therebetween; a shaft secured to said impeller and extending downwardly through said bearing sleeve; sealing means between said shaft and said bearing sleeve to prevent leakage of fluid therebetween; and means for admitting gas into said annular space to form a gas pocket therein.

11. A cleansing machine including, a tank having a downwardly and inwardly sloping bottom; a settling basin secured to said tank and having an outlet and an inclined bottom sloping toward said outlet, said bottoms having aligned apertures; a bearing sleeve extending upwardly through said apertures; means on said bearing sleeve closing the aperture in the basin bottom; an impeller disposed in said tank above said apertures and having a dependent tubular skirt disposed about said bearing sleeve over substantially the whole length of said bearing sleeve, said skirt being spaced from said bearing sleeve to form a cylindrical space therebetween; a shaft secured to said impeller and extending downwardly through said bearing sleeve; sealing means between said shaft and said bearing sleeve to prevent leakage of fluid therebetween, said bearing sleeve being provided with a passage for admitting a gas into said cylindrical space above the lower ends of said skirt and sleeve to form a gas pocket therein whereby the liquid in the tank is prevented from passing upwardly in said cylindrical space.

12. A cleansing machine including, a tank having a downwardly and inwardly sloping bottom; a settling basin

having an outlet and an inclined bottom sloping toward said outlet, said bottoms having aligned apertures; a bearing sleeve extending upwardly through said apertures; means on said bearing sleeve closing the aperture in the basin bottom; an impeller disposed in said tank above said

5 apertures and having a dependent tubular skirt disposed about said bearing sleeve over substantially the whole length of said bearing sleeve, said skirt being spaced from said bearing sleeve to form a cylindrical space therebetween; a shaft secured to said impeller and extending downwardly through said bearing sleeve; sealing means between said shaft and said bearing sleeve to prevent leakage of fluid therebetween, said bearing sleeve being provided with a passage for admitting a gas into said cylindrical space above the lower ends of said skirt and sleeve to form a gas pocket therein whereby the liquid in the tank is prevented from passing upwardly in said cylindrical space, said skirt being provided with means for expelling liquid from said cylindrical space when said

20 impeller is rotated.

13. A cleansing machine including, a tank having a downwardly and inwardly sloping bottom; a settling basin having an outlet and an inclined bottom sloping toward said outlet, said bottoms having aligned apertures; a bearing sleeve extending upwardly through said apertures;

25 means on said bearing sleeve closing the aperture in the basin bottom; an impeller disposed in said tank above said apertures and having a dependent tubular skirt disposed about said bearing sleeve over substantially the

30 whole length of said bearing sleeve, said skirt being spaced from said bearing sleeve to form a cylindrical space therebetween; a shaft secured to said impeller and extending downwardly through said bearing sleeve; sealing means between said shaft and said bearing sleeve to prevent leakage

35 of fluid therebetween, said bearing sleeve being provided with a passage for admitting a gas into said cylindrical space above the lower ends of said skirt and sleeve to form a gas pocket therein whereby the liquid in the tank is prevented from passing upwardly in said cylindrical space, said skirt being provided with a plurality of circumferentially spaced apertures adjacent its lower end whereby liquid is expelled from said cylindrical space when said impeller is rotated.

14. A cleansing machine including, a tank having a downwardly and inwardly sloping bottom; a settling basin having an outlet and an inclined bottom sloping toward said outlet, said bottoms having aligned apertures; a bearing sleeve extending upwardly through said apertures;

45 means on said bearing sleeve closing the aperture in the basin bottom; an impeller disposed in said tank above said apertures and having a dependent tubular skirt disposed about said bearing sleeve over substantially the

50 whole length of said bearing sleeve, said skirt being spaced from said bearing sleeve to form a cylindrical space therebetween; a shaft secured to said impeller and extending downwardly through said bearing sleeve; sealing means between said shaft and said bearing sleeve to prevent leakage of fluid therebetween, said bearing sleeve being provided with a passage for admitting a gas into

55 said cylindrical space above the lower ends of said skirt and sleeve to form a gas pocket therein whereby the liquid in the tank is prevented from passing upwardly in said cylindrical space, said skirt being provided with a helical screw disposed in said cylindrical space for expelling liquid therefrom when said impeller is rotated.

15. A cleansing machine including: a tank having a bottom; a settling basin open at its upper end and connected at said upper end with the bottom of said tank; a bearing sleeve disposed in said basin and extending upwardly through said open upper end into said tank; a shaft rotatably mounted in said bearing sleeve and projecting above the upper end of said sleeve; an impeller mounted on said shaft and having an integral imperforate

70 circular plate disposed adjacent the bottom of said tank and completely overlying the open end of said basin and

a plurality of impeller vanes projecting laterally from said shaft and joined to the upper surface of said circular plate, said impeller also having a tubular skirt depending from the underside of said circular plate surrounding and spaced outwardly from said bearing sleeve, said skirt extending downwardly into said basin along a major portion of the bearing sleeve length; and means connected with said bearing sleeve for conducting air under pressure from exteriorly of said tank and basin into the space between said tubular skirt and bearing sleeve above the lower end of said skirt to prevent entry of liquid into such space.

16. In a machine having a rotatable impeller for circulating liquid; a tubular skirt depending from the impeller; a bearing sleeve extending upwardly into said tubular skirt to form a cylindrical space therebetween; a shaft extending downwardly from said impeller through said bearing sleeve; sealing means between said shaft and said bearing sleeve, said skirt being provided with a plurality of circumferentially spaced apertures adjacent its lower end extending outwardly and rearwardly of the direction of rotation of the skirt whereby liquid is expelled from said cylindrical space when said impeller is rotated; and means connected with said bearing sleeve and communicating with said cylindrical space between said skirt and sleeve above the lower end of said skirt for conducting gas from a remote point into said cylindrical space as liquid is ejected therefrom.

17. In a machine having a rotatable impeller for circulating liquid; a tubular skirt depending from the impeller; a bearing sleeve extending upwardly into said tubular skirt to form a cylindrical space therebetween; a shaft extending downwardly from said impeller through said bearing sleeve; and sealing means between said shaft and said bearing sleeve, said skirt having a helical screw disposed in said cylindrical space and rotatable with said skirt, the turns of the helical screw being inclined upwardly in the direction of rotation of said skirt whereby liquid in said cylindrical space is propelled downwardly of said space toward the lower end of said skirt as said skirt is rotated.

18. A cleansing machine including, a tank having a downwardly and inwardly sloping bottom; a settling basin having an outlet and an inclined bottom sloping toward said outlet, said bottoms having aligned apertures; a

bearing sleeve extending upwardly through said apertures; means on said bearing sleeve closing the aperture in the basin bottom; an impeller having a circular plate; a plurality of fins extending upwardly from said plate; a tubular skirt depending from said plate and disposed about said bearing sleeve over substantially the whole length of said bearing sleeve, said skirt being spaced from said bearing sleeve to provide an annular space therebetween; a shaft depending from said impeller and extending downwardly through said bearing sleeve; and sealing means between said shaft and said bearing sleeve to prevent leakage of fluid therebetween, said bearing sleeve being provided with a passage for admitting gas under pressure into said annular space above the lower ends of said skirt and sleeve.

19. A cleansing machine of the character set forth in claim 1 wherein the tubular skirt is imperforate throughout its length.
